(57) **CLAIM**

The ornamental design for a comb, as shown and described.

DESCRIPTION

FIG. 1 is an isometric view of a first embodiment of a comb showing our new design;

FIG. 2 is an enlarged partial view thereof, showing area 2-2 of FIG. 1;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an isometric view of a second embodiment of a comb showing our new design;

FIG. 10 is an enlarged partial view thereof, showing area 10-10 of FIG. 9;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken line showing of portions of the comb in FIGS. 1, 5-6, 9, and 13-14 represents environmental subject matter and forms no part of the claimed design. The break lines that separate portions of the handle FIGS. 1, 3-6, 9, and 11-14 and the area within the break lines represent indeterminate length and form no part of the claimed design.
